UNITED STATES PATENT OFFICE.

FRANK MCINTYRE, OF NEW YORK, N. Y., ASSIGNOR TO THE EAGLE PENCIL COMPANY, OF NEW YORK.

DESIGN FOR A PENCIL-CASE.

SPECIFICATION forming part of Design No. 31,174, dated July 11, 1899.

Application filed June 15, 1899. Serial No. 720,725. Term of patent 7 years.

To all whom it may concern:

Be it known that I, FRANK MCINTYRE, residing at New York city, in the county and State of New York, have invented and produced a new and original Design for Pencil-Cases, of which the following is a specification, reference being had to the accompanying drawing, which is a plan view of a pencil-case showing my new design.

As shown in the accompanying drawing, the pencil-case has plain reduced upper and lower ends *a* and *b*, respectively, and between these ends are embossed portions, these embossments *c* being of diamond or lozenge shape and formed by lines or grooves *d* arranged and disposed spirally about the pencil-case, the lines or grooves *d* inclining in a direction opposite to that of the lines or grooves *e*. At either end of the embossed

portions is formed a bead *ff'*, and the upper 20 reduced end of the pencil-case is artistically rounded, as at *g*. The lower plain end *h* is gracefully tapered, forming reduced portions 1, 2, and 3, which are divided by beads 5 and 6, as seen in the accompanying drawing. 25

The metallic pencil-case embodying my design produces a pleasing effect upon the eye and is very ornamental in appearance.

Having described my invention, what I claim herein as new, and desire to secure by 30 Letters Patent, is—

The design for a pencil-case as herein shown and described.

FRANK MCINTYRE.
